UNITED STATES PATENT OFFICE.

JAMES ROAKE, OF OREGON CITY, OREGON.

LEVELING DEVICE.

1,014,519.

Specification of Letters Patent.

Patented Jan. 9, 1912.

Application filed May 25, 1911. Serial No. 629,283.

To all whom it may concern:

Be it known that I, JAMES ROAKE, a citizen of the United States, residing at Oregon City, in the county of Clackamas and State of Oregon, have invented new and useful Improvements in Leveling Devices, of which the following is a specification.

My present invention pertains to leveling instruments; and it has for its object to provide a simple, compact and inexpensive device for taking levels in street grading, laying sewers, providing foundations for buildings, etc., the said device embodying a weight that is adapted when properly set to move the tube to its correct position, thereby obviating the necessity of readjusting the device when moved from one point to another.

Other objects and advantageous features of the invention will be fully understood from the following description and claim when the same are read in connection with the drawings, accompanying and forming part of this specification, in which:

25 Figure 1 is a plan, Fig. 2 a longitudinal vertical section with parts in elevation, and Fig. 3 a transverse vertical section of one embodiment of my invention. Fig. 4 is a side elevation of another embodiment of the invention. Fig. 5 is a view, partly in elevation and partly in vertical section taken at a right angle to Fig. 4.

Referring by letter to said drawings, and more particularly to Figs. 1, 2 and 3 thereof:

35 A is the main frame of the device, and B B are screws that bear in the frame sides a, are pointed at their inner ends and are equipped with jam or lock nuts b. Fulfilled between the inner ends of the screws

40 B is a tube C having at one end an eye piece c, and at its opposite end a cross-wire d. The term "tube" is here employed in its broad sense and is intended to comprehend a plain tube such as illustrated, a telescope or any

45 other type of tube consonant with the purpose of my invention. Contained in a metal case D that is fixed on the upper side of the tube C is an ordinary spirit level E, and joined through a shank e with the underside

50 of the said tube C is an open frame F which extends in the direction of the length of the tube and is fixed with respect thereto so as to always move therewith. Fixed in the forward and rear portions of the open frame F are the ends of a longitudinal threaded shaft G, and mounted and adapted

to be adjusted on the said threaded shaft is an interiorly threaded balancing weight H, the exterior of which is preferably roughened as indicated by f to facilitate rotation of the weight about the shaft G when occasion demands adjustment of the weight on the shaft in the direction of the length thereof.

In the use of the instrument the same is placed upon a suitable support, whereupon the weight H will immediately bring the level to a true position, and the line of sight from the eye piece c and across the wire d will form a true horizontal line and can be projected any reasonable distance as required.

The capacity of the weight H to be adjusted on shaft G in the direction of the length of the tube is advantageous since without such adjustment the balancing of the tube C on the pivots would have to be very exact and would be difficult of accomplishment. In other words the weight when correctly positioned on the screw will bring the tube to its correct position which position will be indicated by the spirit level.

It will be gathered from the foregoing that my novel device is simple and inexpensive in construction, and that the arrangement of the balancing weight and the frame in which the same is carried in the main frame renders the device very compact, while permitting of access being readily gained to the weight for the purpose of adjusting the same in its frame.

The mounting of the weight H on screw G permits longitudinal adjustment of the weight in a line parallel to the axis of tube C, and it will also be noted that said weight H is disposed on the perpendicular line of center of gravity from the pivots formed by the screws B. See Fig. 2.

In the modification shown in Figs. 4 and 5, the main frame A' differs only in form from the frame A of Figs. 1-3, and the tube C and its appurtenances are mounted between the sides a' of said frame A' in the same manner as said parts are mounted between the sides a of frame A. The frame A of Figs. 1 to 3 has a flat bottom surface, and is adapted to be rested on any suitable support, while the frame A' of Figs. 4 and 5 is mounted on a plate M, and is adapted to be rotated on a vertical axis perpendicular to the line of sight in the tube C. Said frame A' is provided with a depending por-

tion *m* that is let into a circular aperture in the plate *M*, and is connected to said plate by collar and lock nut, as shown in Fig. 5. It will also be noticed that the plate *M* is provided with lugs *p* for the connection of suitable legs *r* to form a tripod support for the instrument when in use. For the purpose of restricting rotary movement of the frame *A'* on the plate *M*, a clamping means 10 is provided made up of a shoe *s* arranged to bear against the circular depending portion of the frame *A'*, and a screw *t* that bears in the plate *M* and against the said shoe.

When the construction shown in Figs. 4 15 and 5 is employed, the instrument obviously can be rotated on a single resting place, and the operator can get the level of any object within range.

Having described my invention, what I 20 claim and desire to secure by Letters-Patent, is:

A leveling instrument comprising a main

frame having sides, a vertically-swinging sighting tube mounted on pivots between said sides of the main frame, a spirit level 25 arranged on said sighting tube, an open frame extending in the direction of the length of the sighting tube and connected and movable therewith and disposed between the sides of the main frame, a longitudinally-disposed threaded shaft fixed at its ends in the forward and rear portions of the open frame, and an interiorly threaded balancing weight mounted on said shaft and capable of adjustment in the direction 30 of the length thereof.

In testimony whereof I have hereunto set my hand in presence of two subscribing witnesses.

JAMES ROAKE.
